US00D447505B1

(12) **United States Design Patent** (10) Patent No.: **US D447,505 S**
(45) Date of Patent: ** Sep. 4, 2001

(54) **EYEGLASSES**

(75) Inventor: **Henry Welling Lane**, San Luis Obispo, CA (US)

(73) Assignee: **Dioptrix Medical Products, Inc.**, San Luis Obispo, CA (US)

(**) Term: **14 Years**

(21) Appl. No.: **29/135,903**

(22) Filed: **Jan. 19, 2001**

(51) LOC (7) Cl. **16-06**

(52) U.S. Cl. **D16/315**

(58) Field of Search D16/101, 300-330, D16/335; D29/109, 110; 351/41, 44, 51, 52, 103, 109, 111, 158; 2/447, 448
